UNITED STATES PATENT OFFICE

2,462,483

THE CLASP

Julian F. Fontaine, Detroit, Mich.

Application March 12, 1947, Serial No. 734,084

4 Claims. (Cl. 2-154)

1

My improvement pertains to tie clasps for use with pre-formed ties of the bow type variety. The clasp is of a two element construction, one of the elements being mounted on the back part of the tie itself in the center thereof, while the other part is attached to the collar band to which the tie is to be affixed.

The purpose of my improvement is to provide a clasp permitting easy and prompt engagement of the tie to said band to retain the tie in its place with respect to the collar. Another purpose is to provide a clasp which will hold the tie with both wings alined in a normal horizontal position, eliminating the tendency of the ties of the sort to swing at an angle to said collar band so that one wing projects above the line of said band while the other wing is swung below said line. A further purpose of my clasp is to provide means to securely attach the tie in place preventing the possibility of accidental disengagement thereof.

I shall now describe my clasp with respect to the accompanying drawings in which:

Figure 1 is a perspective view of a tie, a supporting band therefor, and of the clasp connecting them together;

Figure 2 is a perspective view of a tie and the elements of my clasp in their disconnected position;

Figure 3 is a top view of the clasp as connecting the tie to the collar band;

Figure 4 is an enlarged plan view of my clasp;

Figure 5 is a bottom view of the clasp from the opposite direction as shown in Figure 3;

Figure 6 is a sectional view on line 6-6 of Figure 4;

Figure 7 is a sectional view on line 7-7 of Figure 6;

Figure 8 is a perspective view of two members of a modified clasp;

Figure 9 is a sectional view on line 9-9 of the clasp shown in Figure 8;

Figure 10 is a perspective view of another species of the clasp.

Similar numerals refer to similar parts throughout the several views.

As shown in the drawings, the pre-formed tie 10 contains on its back side a mounting plate 11 having a depressed central portion 12 and two side flanges 13. A complementary member of the clasp, generally indicated by numeral 14, is made of a strip of sheet metal having a substantially flat central portion 15 looped back at both ends as shown by numeral 16, the strip continuing at each end in a reverse loop 17, and extending

2

parallel to the main portion outwardly. The end portions of the strip marked 18 and 19, respectively, are provided with transversely set two eyes 20 and 21, respectively, as shown in Figure 2. One of said end portions 19 is attached directly to a collar band 21a. The other end of the band is provided with a hook containing member 22 to fit into said eye 20.

The looped portions 16 form receiving vertical 10 folds for flanges 13 of the mounting plate 14 permitting the mounting plate to be brought into engagement with the receiving member 14. This is effected by having flanges 13 enter into respective inner spaces of loops 16. In order to 15 prevent the mounting plate from sliding downwardly out of the receiving member, the latter includes lugs 23 turned from the body of the receiving member to form bottom stops under the respective spaces defined by loops 16.

As another provision to keep the two complementary parts of the clasp in engagement with each other, I provide a locking pin 24. The pin which is horizontally disposed between the end portion 18 of the receiving member 14 and 25 the inner fold of the reverse loop 17, may be shifted through a hole made in said reverse loop 17 into a hole in the mounting plate 11, as best shown in Figure 6.

The pin is bent into an angle to form a head 30 25 projecting outwardly through a slot 29 in the end portion 18 of the receiving member 14 said head serving as a means of shifting said pin manually into engagement with said mounting plate. Numeral 25a shows the head of the pin in the disengaged position of said pin. Lateral extensions 26, integrally connected to the pin, prevent it from falling out of its place.

The modified clasp shown in Figure 8 includes a mounting plate 11 and a receiving member 40 which is formed of one blank of sheet metal having an eye 28 for attachment to one end of the band 21a. Means for engagement of the flanges 13 are made by severing from the body of the receiving member, at each end, on three 45 sides, a rectangular portion 30 and bending it inwardly along its unsevered side to a parallel but spaced position with the central portion 31. In this manner a formation is made similar to that made by loop 16, and serves for reception 50 of flanges 13 of the mounting plate. Bottom lugs 32 are provided to prevent the mounting plates from slipping through downwardly out of the receiving member.

In the clasp shown in Figure 10, it is the 55 mounting plate attached to the back side of the

tie which has flanges 33 looped back upon themselves as shown at 34 so that said flanges may be slipped over the edges 35 of the central rectangular portion 36 of the complementary unit of the clasp. For that purpose the edges of the portion 36 are spaced from the body section of the unit.

It will be obvious that other changes may be made in the construction of my clasp without departing from the inventive principle disclosed herein. What I, therefore, wish to claim is as follows:

1. A two-element tie clasp comprising a substantially rectangular plate mounted on the back side of a tie, and a receiving member, said member being made of one oblong strip of metal, the strip having a center flat portion and being bent at each end upon itself in a loop and continuing outwardly in a reverse loop, the terminal portions of the strip having eyes for connection to a collar encircling band, the first named loops forming receiving folds for insertion of the mounting plate on the tie.

2. A two-element tie clasp of the kind described comprising a mounting plate affixed to the back side of the tie, said plate including a flat center portion and two laterally extending marginal flanges disposed in a plane spaced from the tie, and a receiving member made of an oblong flat strip of rigid material, the strip having a rectangular-shaped central flat portion, and having members looped upon said center portion from opposite sides to form means for a sliding engagement of the flanges of the mounting plate, the looped members continuing in a reverse loop, each being provided with an eye for connection to a collar encircling band.

3. A two-element tie clasp of the kind described comprising a mounting plate affixed to the back side of the tie, said plate including a flat center portion and two laterally extending marginal flanges disposed in a plane spaced from

the tie, and a receiving member made of an oblong flat strip of rigid material, the strip having a rectangular shaped central flat portion and being at each end bent back upon itself to form a loop and then being bent back in the opposite direction to form a reverse loop and a locking pin disposed between the walls of one loop and the reverse loop connected thereto and said locking pin being provided with an externally disposed head for a manual shift of the pin into a hole in the mounting plate for retention thereof in the receiving member.

4. A two-element tie clasp comprising a plate mounted on the back of a tie, the plate including vertical side flanges in a plane spaced from the tie, and a receiving member for said mounting plate, connected to a collar encircling textile band, said receiving member being made of an oblong strip of material, the strip including a rectangular flat center, a pair of members integrally connected thereto and looped from opposite ends over the sides of the flat center to form receiving folds for the flanges of the mounting plate, lugs extending outwardly from the body of the receiving member to close from the bottom the space defined by the loops, and a pin slideably mounted on the receiving member for a manual shift laterally into an aperture in the side of the mounting plate for retention thereof in its place.
